(57) **CLAIM**

The ornamental design for a shaped spindle of a door handle for operating a door lock box, as shown and described.

DESCRIPTION

FIG. 1 is a perspective view of a shaped spindle of a door handle for operating a door lock box showing my new design; FIG. 2 is a top plan view thereof;

FIG. 3 is a front elevational view thereof;

FIG. 4 is a left side elevational view thereof;

FIG. 5 is a right side elevational view thereof;

FIG. 6 is a perspective view of a second embodiment of FIG. 1;

FIG. 7 is an opposite side perspective of FIG. 6;

FIG. 8 is a front elevational view FIG. 6;

FIG. 9 is a perspective view of a third embodiment of FIG. 1;

FIG. 10 is an opposite side perspective view of FIG. 9;

FIG. 11 is a front elevational view of FIG. 9;

FIG. 12 is a perspective view of a fourth embodiment of FIG. 1;

FIG. 13 is an opposite side perspective view of FIG. 12;

FIG. 14 is a front elevational view of FIG. 12;

FIG. 15 is a perspective view of a fifth embodiment of FIG. 1;

FIG. 16 is an opposite side perspective view of FIG. 15; and,

FIG. 17 is a front elevational view of FIG. 15.

The broken lines illustrate the unclaimed portions and environment and form no part of the claimed design.
